US00D529378S

(12) **United States Design Patent** (10) Patent No.: **US D529,378 S**
Spencer et al. (45) Date of Patent: ** Oct. 3, 2006

(54) **PACKAGING**

(75) Inventors: **Yvette Spencer**, Ware (GB); **Paul Richard Smith**, Ware (GB); **Peter David Walker**, Ware (GB)

(73) Assignee: **Glaxo Group Limited** (GB)

(**) Term: **14 Years**

(21) Appl. No.: **29/194,456**

(22) Filed: **Nov. 26, 2003**

(30) **Foreign Application Priority Data**

May 30, 2003 (EM) 38344

(51) **LOC (8) CI.** **09-03**

(52) **U.S. CI.** **D9/433**

(58) **Field of Classification Search** D9/430, D9/433, 428, 730, 702, 713, 710, 732; D24/100, D24/101, 203; D3/201, 203.2, 203.3; 222/1, 222/129, 423, 498, 542; 206/534, 528, 784, 206/828, 532, 534.1, 471, 474, 476, 39.7, 206/459.5, 1.5, 485.1, 525, 823, 531, 538, 206/539, 469, 461-466
